UNITED STATES PATENT OFFICE.

CHARLES S. SEITZ, OF TIFFIN, OHIO.

RAILWAY CONSTRUCTION.

SPECIFICATION forming part of Letters Patent No. 787,003, dated April 11, 1905.

Application filed December 19, 1904. Serial No. 237,515.

To all whom it may concern:

Be it known that I, CHARLES S. SEITZ, a citizen of the United States, residing at Tiffin, in the county of Seneca and State of Ohio, have 5 invented a new and useful Railway Construction, of which the following is a specification.

This invention relates to railway constructions and is designed to effect a strong and durable connection between the rails and the 10 cross-ties without weakening these members by the formation of openings therein and to provide for tightening the connection between the rails and the ties whenever it becomes necessary to take up wear. It is also 15 proposed to provide for shifting the rails laterally for the purpose of changing to and from a narrow gage and also to accommodate rails of different widths.

A still further object of the invention is to 20 provide an improved form of cross-tie for the support of the rails and arranged to facilitate the tamping of ballast into and around the tie.

With these and other objects in view the present invention consists in the combination 25 and arrangement of parts, as will be herein-after more fully described, shown in the accompanying drawings, and particularly pointed out in the appended claims, it being understood that changes in the form, proportion, 30 size, and minor details may be made within the scope of the claims without departing from the spirit or sacrificing any of the advantages of the invention.

In the accompanying drawings, Figure 1 is 35 a side elevation of a portion of a cross-tie of the present invention with a rail in section connected thereto by the means of the present invention, a portion of the tie being broken away to disclose the rail-fastening means. 40 Fig. 2 is a cross-sectional view on the line 2-2 of Fig. 1. Fig. 3 is an enlarged detail perspective view of one end portion of the cross-tie of the present invention. Fig. 4 is a detail perspective view of the anchor-plate or 45 lower clamp member of the rail-fastening. Fig. 5 is a detail perspective view of the upper clamp member of the rail-fastening means. Fig. 6 is a view similar to Fig. 1, illustrating a modification.

50 Like characters of reference designate cor-

responding parts in each and every figure of the drawings.

Referring at first more particularly to Fig. 3 of the drawings, it will be seen that the cross-tie of the present invention is rectangular and hollow in the nature of a channel-bar, including a flat base 1, upstanding sides 2, and external longitudinal base-flanges 3, the outer longitudinal edges of which are inclined or flared upwardly, as indicated at 4. 55 At corresponding intervals from each end of the tie the upstanding sides 2 have corresponding portions 5 cleft therefrom and bent inwardly to produce internal substantially horizontal flanges, which constitute a depressed 60 seat for the reception of a rail, (designated 6 in Figs. 1, 2, and 6 of the drawings.) As is best indicated in Fig. 2 of the drawings, the advantage of this form of cross-tie will be understood, for it permits of the ballast 7 70 being placed within the tie, as well as upon the external base-flanges 3, the upwardly flared or deflected edges of the latter operating to more effectually retain the ballast upon the flanges than if the latter were entirely 75 flat, while at the same time the upwardly-inclined edges of the flanges permit of the ballast being tamped beneath the flanges, thereby to embed the latter in the ballast, and thus insure a strong and durable anchoring of the tie. 80

For connecting the rail to the tie I employ upper and lower clamp members 8 and 9, respectively, of which the lower member 9 is in the nature of a flat substantially oblong plate or bar of a width to fit between the sides of 85 the tie and underlap the flanges or rail-seat members 5 and of a length to project at opposite edges of the base of the rail, one end of the member being formed into an upstanding hook 10 to embrace the adjacent edge of the 90 base of the rail, while its other end is provided with a bolt-opening 11, located outwardly from the opposite edge of the base of the rail. The upper clamp member 8 rests upon the rail-seat members 5 and is provided with an 95 upwardly-inclined tongue or extension 12 to lie upon the top of the adjacent base portion of the rail, the opposite edges of the clamp member being provided with pendent flanges 13, which externally embrace opposite sides of 100

the tie. Upon the upper side of the clamp member 8 there is a boss 14, which is pierced by a bolt-opening 15, in alinement with the bolt-opening 11 of the lower clamp member 9, there being a bolt 16 passed through these bolt-openings with its head lying against the under side of the lower member 9 and a nut 17 fitted to its upper end and bearing against the boss 14. It will here be noted that the bolt 16 is inclined to the vertical, and therefore the upper face of the boss 14 is given the proper inclination to permit of the nut 17 fitting flat thereagainst, and the under side of the lower clamp member 9 is provided with a cam-shaped boss 18, arranged to have the head of the bolt engaged flat thereagainst. As clearly indicated in Fig. 1 of the drawings, it will be noted that one longitudinal edge of the base of the rail, preferably that which is at the outer side of the track, engages the corresponding upstanding shoulders 19, formed by the displacement of the tie portions 5, thereby to prevent outward lateral displacement of the rail under the weight of passing trains, while the outer end of the upper clamp member 8 engages the corresponding shoulders 20 of the tie, so as to prevent inward displacement.

From the foregoing description it will be noted that the bolt 16 passes through the clamping members only at one side of the rail and between the rail-seat members 5, whereby neither the rail nor the tie is weakened by bolt-openings and the two clamp members can be readily drawn together by tightening the nut 17 when it is necessary to take up looseness in the clamp members occasioned by wear. Moreover, the rail is connected to the tie by reason of the lower clamp member 9 underlapping the rail-seat members 5, while the hook 10 thereof and the portion 12 of the upper clamp member embraces the top of the base of the rail, thereby to effectually retain the latter seated snugly upon the seat members 5. If desired, the wooden block 21 may be placed within the tie and against the under side of the lower clamp member 9, so as to in a measure deaden the noise occasioned by the passage of car-wheels.

It is preferred to locate the bolt 16 at the inner side of the rail, with the outer edge of the base-flange engaging the shoulders 19, adjacent the outer end of the tie, as the shoulders will effectually prevent lateral outward displacement of the rail by the pressure of wheel-flanges, while the rail-clamping members at the inner side of the rail are intended to prevent outward tilting of the rail under the same strains.

The rail-seat is of course somewhat wider than the base of the widest rail to accommodate the body portion of the upper clamp member 8 and also to accommodate rails of different widths and to permit of a rail being

shifted inwardly, so as to decrease the gage of the track whenever necessary, as indicated in Fig. 6 of the drawings. In this figure the rail 6 and the cross-tie are the same as hereinbefore described; but the lower clamp member 22 is not provided with a hook, but is provided at each end with a boss 23 upon its under side, which is pierced by the bolt-opening 24, and in the place of the hook 10 there is another upper clamp member, 25, which is a duplicate of the opposite clamp member 8 and is connected to the lower clamp member in the same manner. With this construction the clamp member which is at the outer side of the rail of course engages the adjacent upright shoulder of the rail-seat, so as to be braced against the strains occasioned by the pressure of wheel-flanges, while the other clamp member may or may not engage the other shoulder, according to the width of the rails.

Having fully described the invention, what is claimed is—

1. The combination of a hollow tie having an open top with opposite internal longitudinal flanges, a rail extending across the flanged portion of the tie, upper and lower clamp members embracing the base of the rail and the flanges of the tie and projected beyond the rail, and an upright fastening piercing the clamp members at one side of the rail and capable of adjustment to take up wear.

2. The combination of a hollow tie having an open top with corresponding portions cleft from the opposite sides of the tie and bent inwardly to form rail-seat members, a rail supported upon the seat members, upper and lower clamp members embracing the base of the rail and the rail-seat members and projected beyond the rail, and a fastening piercing the clamp members at one side of the rail and adjustable to take up wear.

3. The combination of a hollow tie having an open top with opposite internal longitudinal flanges, a rail upon the flanged portion of the tie, a lower clamp member underlapping the flanges and projected to one side of the rail, an upper clamp member overlapping the base of the rail and the projected portion of the lower clamp member and provided with pendent flanges embracing the tie, and an upright fastening piercing the clamp member at one side of the rail and capable of adjustment to take up wear.

4. The combination of a tie having an open top with portions cleft from opposite sides thereof and bent inwardly to form rail-seat members, a rail supported upon the seat members and engaging the corresponding shoulders at one side of the seat, and clamping means embracing the base of the rail and seat members and engaging the shoulders at the other side of the seat.

5. The combination of a hollow tie having an open top with portions cleft from opposite

sides thereof and bent inwardly to form depressed rail-seat members, a rail supported upon the seat members with its base engaging the shoulders at one side of the seat, rail-clamping means embracing the base of the rail and the seat members and engaging the shoulders at the other side of the seat, and fastening means piercing the clamping members at one side of the rail and capable of adjustment to take up wear.

6. The combination of a hollow tie having internal flanges, a rail supported upon the flanged portion of the tie, a lower clamp member underlying the flanges and provided with a hook embracing one edge portion of the base of the rail and projected at the opposite side of the rail, a clamp member engaging the upper face of the other side of the base of the rail and the adjacent portion of the lower clamp member, and an upright fastening piercing the two clamp members at one side of the rail and capable of adjustment to take up wear.

7. The combination of a hollow tie having portions cleft from opposite sides thereof and bent inwardly to form depressed seat members with shoulders at opposite sides thereof, a rail supported upon the seat members and engaging the shoulders at one side thereof, a lower clamp member underlying the seat members with one end provided with a hook embracing one side of the base of the rail with its other end projected beyond the rail, an upper clamp member engaging the upper face of the other side of the base of the rail and the other shoulders of the seat, and a fastening piercing the clamp members at one side of the rail and capable of adjustment to take up wear.

8. As a new article of manufacture, a tie in the form of a channel-bar having an open top and provided with opposite external longitudinal base-flanges having their outer edges flared upwardly and outwardly.

9. As a new article of manufacture, a tie in the form of a channel-bar having a closed bottom and an open top, corresponding portions of the upper edges of the opposite sides of the tie being cleft and bent inwardly to form depressed seat members and the base of the tie

being provided with opposite external longitudinal flanges having their outer edges flared upwardly and outwardly.

10. The combination of a tie provided with opposite longitudinal flanges, a rail extending across the flanged portion of the tie, upper and lower clamp members embracing the base of the rail and the flanges of the tie and projected beyond the rail, and an upright fastening piercing the clamp members at one side of the rail and capable of adjustment to take up wear.

11. The combination of a tie provided with opposite longitudinal flanges, a rail extending across the flanged portion of the tie, upper and lower clamp members embracing the base of the rail and the flanges of the tie, and an upright fastening piercing the clamp members and capable of adjustment to take up wear.

12. The combination of a hollow tie having corresponding portions cleft from opposite sides thereof and bent into substantially horizontal flanges, a rail supported across the tie at the flanged portion thereof, upper and lower clamp members embracing the base of the rail and the flanges, and fastening means piercing the clamp members and capable of adjustment to take up wear.

13. The combination of a tie having a longitudinal flange, a rail seated across the flanged portion of the tie, a lower clamp member extending across the under side of the flange with one end provided with means to embrace the adjacent end of the flange and the adjacent edge of the base of the rail, the opposite end of the clamp member being projected beyond the opposite side of the rail, an upper clamp member embracing the base of the rail and the projected portion of the lower clamp member, and a fastening piercing the projected portions of the clamp members and adjustable to take up wear.

In testimony that I claim the foregoing as my own I have hereto affixed my signature in the presence of two witnesses.

CHARLES S. SEITZ.
